UNITED STATES PATENT OFFICE.

HENRY RENBEL, OF NEW YORK, N. Y.

DESIGN FOR A STAIR-BUTTON.

SPECIFICATION forming part of Design No. 24,081, dated March 5, 1895.

Application filed February 1, 1895. Serial No. 537,020. Term of patent 7 years.

To all whom it may concern:

Be it known that I, HENRY RENBEL, a citizen of the United States, residing at New York, in the county and State of New York, 5 have invented and produced a new and original Design for Stair-Buttons, of which the following is a specification, reference being had to the accompanying drawing, which illustrates my said design.

10 The leading feature of my design consists in a semi-circular surface, the curved portion of which is scalloped, decorated as follows: Around the screw-hole, beads *a* are arranged in a circle from which raised pearl-shaped 15 leaves *b* are radiating in form of an open fan. The leaves are bordered with small beads or dots *c*. Rosettes *d* consisting of eight leaves radiating from a center-bead are so arranged

beyond the radiating leaves *b*, that one rosette *d* is located between the upper ends of two 20 adjoining leaves. Round-headed stems *e* project from the upper ends of the radiating leaves *b* and separate the rosettes *d* from each other, with the exception of the two lowest leaves *b*, from which no such headed stems 25 project.

What I claim is—

The design for stair-buttons herein shown and described.

Signed at New York, in the county and 30 State of New York, this 24th day of December, 1894.

HENRY RENBEL.
